UNITED STATES PATENT OFFICE.

VERNON E. COOK, OF UTICA, AND LEO R. H. BURTON, OF ROME, NEW YORK.

DESIGN FOR A MASS-CARD HOLDER.

Application filed October 14, 1922. Serial No. 3,965. Term of patent 14 years.

To all whom it may concern:

Be it known that we, VERNON E. COOK and LEO R. H. BURTON, citizens of the United States, residing respectively at 14 Richardson Place, Utica, Oneida County, New York, and 109 West Garden Street, Rome, Oneida County, New York, have invented a new, original, and ornamental Design for a Mass-Card Holder, of which the following is a specification, reference being had to the accompanying drawings, forming part thereof.

The drawing shows in Fig. 1 a front perspective view and in Fig. 2 a rear perspective view on a somewhat larger scale of the upper part of the mass card holder showing our new design.

We claim:

The ornamental design for a mass card holder as shown.

VERNON E. COOK.
LEO R. H. BURTON.
